EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

ELECTRIC SWITCH

Application filed December 1, 1930. Serial No. 499,138.

This invention relates to certain new and useful improvements in electric switches and refers more particularly to lighting switches for use with automotive vehicles and especially that type mounted at the lower end of a steering column.

In switches of this type an actuating stem extends axially through the steering column to transmit motion from a switch handle 10 mounted at the upper end of the column to the movable elements of the switch mechanism, and heretofore difficulty has been experienced in providing a secure connection between the actuating stem and the movable 15 elements of the switch mechanism. Various methods have been employed, but all have proven objectionable for one cause or another, and hence it is an object of this invention to improve the driving connection between 20 the actuating stem or rod and the movable elements of a switch mechanism of this type.

Another object of this invention is to provide a switch structure of the character described having a driver for its movable element 25 which extends outside the enclosing casing at the side remote from the terminal head and has simple and efficient means for securely locking the same to the actuating stem.

30 And a further object of this invention resides in the specific manner of securing the driver to the actuating stem.

With the above and other objects in view which will appear as the description proceeds, 35 my invention resides in the novel construction, combination and arrangement of parts substantially as hereinafter described and more particularly defined by the appended claims, it being understood that such changes 40 in the precise embodiment of the herein disclosed invention may be made as come within the scope of the claims.

In the accompanying drawing I have illustrated one complete example of the physical embodiment of my invention constructed 45 according to the best mode I have so far devised for the practical application of the principles thereof, and in which:

Figure 1 is a transverse sectional view 50 taken through a switch structure embodying

my invention, the view being taken on the plane of the line 1-1 of Figure 2;

Figure 2 is a cross sectional view of the switch structure with parts broken away and in section to illustrate structural details taken 55 through Figure 1 on the plane of the line 2-2;

Figure 3 is a cross sectional view taken 60 through Figure 1 on the plane of the line 3-3;

Figure 4 is a detail sectional view taken 65 through Figure 2 on the plane of the line 4-4; and

Figure 5 is a detail sectional view taken 70 through Figure 3 on the plane of the line 5-5.

Referring now more particularly to the accompanying drawing, in which like numerals designate like parts throughout the several views, the numeral 5 represents a 75 substantially cup shaped casing in which the switch mechanism indicated generally by the numeral 6, is housed. The open side of the casing 5 is closed by a terminal head 7 secured in position by tangs 8 projected 75 from the peripheral edge of the casing and struck over the outer surface of the terminal head. The terminal head mounts a number of stationary contacts 9 which have terminal members 10 electrically connected therewith 80 to afford means for connecting outside conductors with the stationary contacts.

Selectively engageable with the stationary contacts 9, which are circumferentially disposed on the terminal head, is a movable 85 contactor 11 comprising a metal ring 12 having a plurality of rounded projections 13 for selective engagement with the stationary contacts. The metal ring 12 abuts against a carrier plate 14 formed of insulating material or the like and is non-rotatably connected therewith by lugs 15 projected from the metal ring and received in suitable notches 16 formed in the periphery of the plate.

Rotation is imparted to the plate 14 and 90 consequently the movable contactor assembly, through a driver indicated generally by the numeral 17. The driver has a central projection 18 which extends through an aperture 19 in the closed wall of the casing 100

5 and through a central opening 14' in the carrier plate to have its extreme end journaled in an opening 20 in the terminal head.

10 A non-rotatable but axially movable connection is afforded between the driver extension and the plate 14 by a pair of diametrically opposite elongated lugs 21 projected from the extension 18 and received in suitable recesses communicating with the opening 14' 15 in the carrier plate.

An annular flange 22 formed on the central portion of the driver 17 abuts the inner surface of the closed wall of the casing about the peripheral edge of its opening 19 15 and thus restrains longitudinal movement of the driver 17 outwardly of the casing, and an expansive spring 23 confined between the carrier plate 14 and the annular flange 22, which is recessed, as at 24, to receive the end 20 of the spring, yieldably urges the carrier plate and consequently the entire movable contactor assembly toward the terminal head to provide the desired contact pressure.

The driver 17 is preferably die cast and 25 has a lug or projection 25 of truncated conical shape extended beyond the closed wall of the casing. On one side the lug has an enlargement 26 in which a threaded opening 27 is formed to receive a set screw 28. The 30 set screw 28 is adapted to bear against the adjacent portion of a tubular actuating stem 29 received in an opening 30 extending longitudinally through the driver 17.

The opening 30 in which the tubular actuating stem 29 is received is cylindrical from that end of the driver journaled in the terminal head aperture to a point substantially in line with the annular flange 22 and the remainder of the opening is substantially 35 elliptical, as at 31, with the short axis of the oval in a plane coinciding with the axis of the set screw 28.

Tightening of the set screw 28 thus causes that portion of the tubular actuating stem 29 disposed within the oval shaped opening 31 to be deformed as illustrated in Figures 2 and 4 thus securing the driver 17 against movement with respect to the actuating stem. The actuating stem being tubular, 40 re-acts against the flat end of the set screw with an elastic pressure somewhat like that of a lock washer and thus prevents slackening back of the screw by vibration.

The movable element of the switch mechanism has approximately 90 degrees of motion and the set screw is so located with respect to this motion as to be readily accessible when the switch mechanism is in its position of 45 use, and by reason of the fact that the means for securing the driver to its actuating stem is disposed on that side of the switch mechanism remote from the terminal head, the possibility of short-circulating the terminals by 50 tools during assembly and disassembly of the

switch mechanism from the steering gear, is entirely eliminated.

Any manner of mounting the switch mechanism may be employed and in the present instance a mounting bracket 32 is riveted or otherwise secured to the closed wall of the casing. It is noted that the mounting bracket is disposed to one side of the longitudinal axis of the switch mechanism and has a substantially semi-circular recess therein to accommodate the driver. This off-set position of the mounting bracket 32 permits the set screw to be positioned close to the closed wall of the casing and permits the 90 degrees of motion on the part of the set screw in a space 75 unrestricted by the mounting bracket or its attaching means.

The limits of movement of the driver and consequently the entire movable assembly of the switch mechanism are defined by the engagement of either of a pair of lugs 33 on the driver with an abutment 34 directed into the interior of the switch casing and preferably formed by striking a portion of the metal of the closed wall of the casing inwardly, 80 as best shown in Figure 5.

From the foregoing description, taken in connection with the accompanying drawing, it will be readily apparent to those skilled in the art to which an invention of the character described appertains that I provide a novel means for drivingly connecting the movable element of a switch of the character described with its actuating medium, whereby assembly and disassembly of the switch mechanism with a steering gear is greatly facilitated, and wherein loosening of the switch driver from its actuating medium is precluded.

What I claim as my invention is:

1. In an electric switch mechanism of the character described including a movable contactor, means for moving the contactor comprising a driver having a substantially elliptical opening, a cylindrical actuator disposed in said opening and having a diameter equal to the minimum diameter of said ellipse, and means for deforming the actuator within said opening to secure the driver against movement with respect to the actuator.

2. In a switch mechanism of the character described including a movable contactor, means for moving the contactor comprising a driver having an opening therein part of which is non-cylindrical, an actuator stem received in said opening, and means for deforming that part of the actuator stem disposed in the non-cylindrical shaped portion of the opening whereby the driver is secured against movement with respect to the actuator.

3. In a switch mechanism of the character described including a movable contactor, means for moving the contactor comprising a driver having an operative connection with the contactor and having an opening therein

partially cylindrical and partially non-cylindrical, a tubular actuator stem received in said opening, and means carried by the driver for deforming that portion of the actuator stem within the non-cylindrical part of the driver opening whereby the driver is secured against movement with respect to the actuator.

4. In a switch mechanism of the character described, including a movable contactor, means for moving the contactor comprising a driver having an operative connection with the contactor and having an opening therein part of which is cylindrical and part of which is non-cylindrical, a tubular actuator stem extended into the driver opening, and a set screw threaded in the wall of the driver for engagement with the tubular actuator stem portion within the non-cylindrical part of the opening for deforming said part, whereby the driver is fixed to the actuator stem and the deformed portion of the actuator stem exerts an elastic pressure on the set screw to prevent retrograde movement thereof.

25 5. In a switch mechanism of the character described including a substantially cup shaped casing and a movable contactor therein, means for imparting movement to the contactor comprising a die-cast driver having a part disposed within the casing and operatively connected with the contactor, an actuator stem for moving the driver, and means outside the closed wall of the casing to deform the actuator stem whereby the stem is secured to the driver.

6. In a switch of the character described including a cup shaped housing and a movable contactor within said housing, a driver having a portion disposed within the casing operatively connected with said contactor and a portion projecting beyond the bottom of said cup shaped housing, said driver having an aperture therein, an actuator within said aperture and means on said projection to deform said actuator whereby relative movement between the actuator and the driver is precluded.

In testimony whereof I have hereunto affixed my signature.

50 EDWARD N. JACOBI.
